WRINGER AND THE LIKE

Walter L. Kauffman, II, Erie, Pa., assignor to Lovell Manufacturing Company, Erie, Pa., a corporation of Pennsylvania

Application October 5, 1939, Serial No. 298,099

5 Claims. (Cl. 68—263)

Wringers are commonly provided with release mechanisms by which the pressure may be instantly released in case of accident. They are also provided with a reset mechanism by which they may be quickly reset. The reset mechanism of the present invention is operable with the release device. Features and details of the invention will appear from the specification and claims.

A preferred embodiment of the invention is illustrated in the accompanying drawing as follows:

Fig. 1 shows a front elevation of a wringer, partly in section.

Fig. 2 an end view of a wringer with the reset lever removed.

Fig. 3 a perspective view of a latch.

Fig. 4 a section on the line 4—4 in Fig. 1.

Fig. 5 a detached view of an end of a trip lever.

Fig. 6 a sectional view of a portion of a stile on the line 6—6 in Fig. 4 showing the trip bar connection therewith.

Fig. 7 a similar view with a different position of the trip bar.

1 marks a base of a wringer, 2 and 2a stiles extending upwardly from a base, 3 a top bar for the wringer frame. Wringer rolls 4 and 5 are mounted on the frame, the rolls having shafts 6 and 7 respectively. The shaft 6 is journaled in bearings 8 arranged in the stiles and resting on the base. The shaft 7 is journaled in bearings 9 slidingly mounted in the stiles. A spring 10 operates on the upper bearings and exerts pressure on the rolls.

The top bar has an interlocking detachable connection 11 at one end of common construction.

At the opposite end of the top bar there is a reset lever 12 which is hinged on the top bar at 13. The reset lever is of channel form forming an interior pocket. It is connected with the stile through links 14, each link being pivotally connected at 15 with an ear 15a on the stile and to a pin 16 secured to the lever. The links and lever form a toggle by which the top bar may be pulled down to reset the pressure in a well known manner.

A latch 17 is carried by an arm and engages the rod 16 and locks the resetting lever in set position. The latch bar is extended by a fork 18 extending both sides of the stile 2 and going through slots 19 in a front to back portion of the wall of the stile. The arms 18 have perforations 20 and pivot pins 21 pass through these perforations and the stile wall, pivotally mount-

ing the latch bar on the stile. The latch bar has front to back portions 22, these portions 22 of the arms 18 being adjacent to slots 23 in the front to back portions of the walls of the stile.

5 Trip bars 24 extend across the wringer and have downwardly extending arms. The arms at the reset end of the wringer are provided with flat portions 25a, the flat portions being formed by bending the ends of the arms providing outwardly extending portions 25, return bends 26, and hook portions 27 at the inner end of the return bends, the flat portions 25a being on the return bends adjacent the hooks. The arms opposite the reset end of the wringer have bent ends 15 which extend into slots similar to 25 in the stile. The arms of the trip bars are sprung apart to permit the insertion of the assembly of the bent ends of the arms into the slots 23 of the wringer.

A spring 17a yieldingly pulls the latch arms 20 upwardly and locates the top surface of these latch arms under the flat portions 25a and holds the flat portions normally in contact with the upper edges of the slots 23, thus yieldingly locating the trip bar 24.

A cam surface 28 is arranged on the latch plate opposite the catch 17 and this operates on the rod 16 to force it outwardly and with it the lever 12 when the latch arm is depressed.

In the operation of the device, when the trip bar is moved inwardly or outwardly, one edge or the other of the flat portion 25a operating as a fulcrum against the upper edge of the slot 23 forces the opposite edge of the portion downwardly and this, operating on a cross portion 22 of the arms, depresses the latch plate, releases the hook 17, and at the same time, through the cam 28 forces a release movement of the setting lever. Preferably the setting lever is set at approximately neutral so that the friction on the surfaces of the catch 17 and the cam 28 in a release movement is very little, and the friction of the rocking parts of the trip lever is reduced to a minimum so that a very sensitive yet very simple release is achieved.

45 45 What I claim as new is:

1. In a wringer or the like, the combination of 50 a frame having top and bottom members; rolls mounted in the frame; a toggle comprising a re-setting lever detachably connecting the top and bottom members; a latch securing the lever in set position, said latch being mounted on the frame and having a portion extending in a direction from front to rear of the wringer; and a trip bar mounted on the frame and having a flat 55 portion engagning the front to rear portion, the

flat portion at an edge operating as a fulcrum and the flat portion at the edge opposite the fulcrum acting on the latch to trip the same.

2. In a wringer or the like, the combination of a frame having top and bottom members having stiles, one of said stiles having walls, portions of which extend in a direction from front to rear of the wringer, one of said portions having a slot; rolls mounted in the frame; a pressure means for the rolls; a release device for the pressure means, said release device having a latch; and a trip bar having a flat portion at one end extending into the slot in the stile, said flat portion at one edge forming a fulcrum and the flat portion at the opposite edge engaging the latch to trip the release.

3. In a wringer or the like, the combination of a frame having top and bottom members having stiles, said stiles having walls, portions of which extend from front to rear of the wringer and at each end of the wringer, the front and rear extending portions having slots through the walls thereof; rolls mounted in the frame; a pressure means for the rolls; a release device for the pressure means, said release device having a latch with arms extending through the front to rear walls of one of the stiles; and trip bars at the front and rear of the wringer, said trip bars being of resilient material and having arms at their ends, the arm at one end of said bar having a flat portion arranged in a slot, the resilience of the arms permitting the assembly of the flat portion in the slot, the flat portion at one edge forming a fulcrum and the flat portion at the edge opposite the fulcrum engaging a portion of the latch to release the release device.

4. In a wringer or the like, the combination of a frame having top and bottom members; rolls mounted in the frame; a toggle comprising a resetting lever detachably connecting the top and bottom members; a latch securing the lever in set position, said latch being mounted on the frame and having a portion extending in a direction from front to rear of the wringer; and a trip bar mounted on the frame and having a flat portion engaging the front to rear portion, the flat portion at one edge operating as a fulcrum and the flat portion at the edge opposite the fulcrum acting on the latch to trip the same.

5. In a wringer or the like, the combination of a frame having top and bottom members having stiles, one of said stiles having walls, a portion of which extends in a direction from front to rear of the wringer, said portion having a slot; rolls mounted in the frame; a pressure means for the rolls; a release device for the pressure means, said release device having a latch; and a trip bar of resilient material having an operative portion extending along the wringer and arms at each end, one of the arms having a flat portion extending into said slot, the resilience of the arms permitting of the springing of the trip bar to assemble the flat portions in the slot, the flat portion at its edges operating on the wall of the slot forming fulcrums for the movement of the flat portion at the edge opposite the edge forming the fulcrum for operating the latch to release the pressure.

WALTER L. KAUFFMAN, II.
